UNITED STATES PATENT OFFICE.

EDWARD C. THURNAU, OF CHICAGO, ILLINOIS.

CIGAR-BOX OR SIMILAR RECEPTACLE.

SPECIFICATION forming part of Letters Patent No. 732,664, dated June 30, 1903.

Application filed August 21, 1902. Serial No. 120,506. (No model.)

To all whom it may concern:

Be it known that I, EDWARD C. THURNAU, a citizen of the United States, residing at Chicago, in the county of Cook and State of Illinois, have invented certain new and useful Improvements in Cigar-Boxes or Similar Receptacles; and I do hereby declare the following to be a full, clear, and exact description of the invention, such as will enable others skilled in the art to which it appertains to make and use the same.

My invention relates to a novel construction in a cigar-box or similar receptacle, the object being to provide a device of this character having a partially-disappearing cover, which when said box is placed in a showcase will prevent obstruction of the view of other boxes and their contents to the smallest possible extent; and it consists in the features of construction and combination of parts hereinafter fully described and claimed.

In the accompanying drawings, illustrating my invention, Figure 1 is a perspective view of a box constructed in accordance with my invention, showing the same open with the cover projecting from the well. Fig. 2 is a transverse section of the box on the line 2-2 of Fig. 1.

Referring now to said drawings, A indicates the box, provided with rear and side walls of the same height, between which the cover B fits, and with a lower front wall upon which the forward end of the cover B is adapted to rest when the box is closed. The rear edge of the cover B is adapted to rest against the inner face of the rear wall. Inwardly of and parallel with said rear wall is a second wall C, equal in height with said front wall and upon which the cover B also rests. Said inner wall C is provided midway between its ends with a longitudinal recess D, and below the latter are two converging recesses E, which are adapted to receive a rubber band F, which latter also engages a staple G on the lower face of the cover B adjacent its forward end. Between said rear wall and said inner wall C a well H is formed, which is adapted to receive the rear end portion of the cover when the box is open, said cover being held by said rubber band F normally in close contact with the rear wall and causing it when turned to recede into the

well and holding it therein in an obvious manner. The said rubber band F is so attached that it spans the front face of the inner wall C, passing rearwardly through said recesses E and then over the upper edge of said inner wall within the recess D, which latter protects it from the pressure of the cover and prevents it from being cut thereby. Obviously by this means the cover of the box is prevented from obstructing so much of the display-space of a show-case as in the ordinary cigar-box and better serves the purpose of a handle by which to grasp and remove the box, the cover being adapted to bind in the well and prevent slipping.

I claim as my invention—

1. A cigar-box or similar receptacle provided at its rear end with two walls between which is a well, the inner wall being of less height than the outer and provided in its upper edge with recesses, a cover resting upon said inner wall and against the inner face of the outer wall, and a rubber band or the like secured to the lower face of the cover and secured in said recesses in said inner wall, said rubber band being adapted to normally draw said cover rearwardly and downwardly into said well.

2. A cigar-box or similar receptacle provided at its rear end with two parallel walls between which a well is formed, the inner wall being lower than the outer and forming a rest and fulcrum on which the cover turns, a recess in the upper edge of said inner wall, recesses extending downwardly from said first-named recess and converging toward each other at their lower ends, a cover, and a rubber band passing through said recesses and secured to the lower face of said cover, said band spanning the inner face of said inner wall and passing over the upper edge of same from the rear and lying within said first-named recess, said band being adapted to draw said cover partially into said well when said cover is raised.

3. A cigar-box or similar receptacle provided with a cover and a double wall in which is a well adapted to receive the cover, said double wall being composed of two parallel walls the inner one of which is of less height than the outer, so that said cover rests against the outer wall and is flush with the upper

edge of the latter, and bands securing said cover to one of said walls, said bands being of such length and so secured as to permit of pivotal and longitudinal movement of said cover, whereby the latter when opened may be inserted in said well without being detached.

In testimony whereof I affix my signature in presence of two witnesses.

EDWARD C. THURNAU.
